HEADLAMP LENS

Howard C. Mead, Anderson, Ind., assignor to General
Motors Corporation, Detroit, Mich., a corporation of
Delaware

Application August 29, 1955, Serial No. 37,690

Term of patent 14 years

(Cl. D48—32)

Figure 1 is a front elevational view of a headlamp lens, showing my new design; and

Figure 2 is a top plan view of the headlamp lens.

I claim:

The ornamental design for a headlamp lens, substantially as shown.
